Attorneys

UNITED STATES PATENT OFFICE.

GILBERT LOKEN, OF SEATTLE, WASHINGTON, ASSIGNOR OF ONE-HALF TO U. J. RAYMOND, OF SEATTLE, WASHINGTON.

SAWYER'S TAPER REGISTER.

Application filed October 27, 1921. Serial No. 510,927.

To all whom it may concern:

Be it known that I, GILBERT LOKEN, a citizen of the United States of America, and resident of the city of Seattle, in the county 5 of King and State of Washington, have invented certain new and useful Improvements in Sawyers' Taper Registers, of which the following is a specification.

My invention relates to sawmill set-works 10 and particularly to a dial or register which is connected with the set-works and which indicates to the sawyer the exact setting of each of the head blocks or knees.

An object of my invention is to provide 15 means which are automatically controlled by the setting of the various knees to indicate this setting.

Another object is to provide such a register which may be so positioned upon the 20 set-works carriage that it will be always readable from the sawyer's station.

A further object is to provide a register for such a purpose which is compact, simple, convenient in use, requiring no attention 25 ordinarily, which is automatic in its operation, and easy to adjust.

Other objects may be ascertained in a study of the following specification and claims.

30 My invention comprises those novel parts and combinations thereof which are shown in the accompanying drawings, described in the specification and particularly defined by the claims terminating the same.

35 In the accompanying drawings I have shown my invention in the forms which are now preferred by me.

Figure 1 is a general perspective view of 40 a set-works carriage with my device mounted thereon.

Figure 2 is an elevation, with parts broken away, of my register.

Figure 3 is a section through a slightly modified form of register.

45 In sawmill set-works the sawyer, who is at a stationary point adjacent the saw, has no means of telling what is the setting of the various knees carried by the carriage. If the sawyer knows from the setting of the 50 knees the width of a timber upon the carriage, he is better able to judge the proper sizes of timbers to be sawn therefrom. Further, in shaping up a log by the method shown in patent to Haley, No 1,393,529, 55 where the first cuts are taken off parallel

to the bark, and then the butt end is set out to take off a wedge, the sawyer must know how far the butt end knee must be set out to bring it even with the knee at the small end. According to my invention, a register 60 which will be automatically controlled by the setting of the knees will show to the sawyer the exact setting of each knee. This will be mounted at a convenient place upon the set-works carriage.

Upon the set-works carriage 1, which supports the log indicated by the dotted lines L, are supported two or more knees 11, these being movable transversely of the carriage 1. The position of each knee is controlled by 70 the rotation of a shaft 12 which in turn is rotated by a longitudinal control shaft which is shown as formed in sections 13, one section corresponding to each of the knees 11. The various sections 13 of the shaft may be 75 connected to rotate together at will by means of a suitable clutch 14. The various sections may be independently rotated when the clutch 14 is disengaged, by suitable means, such as the ratchet levers 15. By providing 80 a sectional control shaft it is possible to set one of the knees 11 nearer the path of the saw than the other. In this way in sawing taper logs it is possible to take off a strip 85 parallel with the bark rather than parallel with the heart of the log, and then to set the knees properly to take off a wedge.

My register is composed of a plurality of rotatable or otherwise movable elements, such as the sleeves 2. Each of these elements 2 is independent of the others in its movement and each is connected suitably to its respective section 13 of the control shaft. As shown in Figure 1 a sprocket chain 16 connects a sprocket upon a section 13 of the 95 control shaft and a sprocket 17, which sprocket 17 connects through a shaft 18 and universal joints 19 to a stub shaft 20. The provision of the universal joints permits the device to be set angularly relative to the 100 shaft sections 13. The shaft 20 is provided with means for rotating the elements 2, such as the elongated spur gear 21 meshing with an internal gear 22 carried by each of the sleeves 2.

105 The sleeves 2, of which two only are shown for purposes of illustration, are mounted upon a shaft 23 to rotate and to be axially movable thereupon. A suitable casing 3 encloses all of the sleeves 2. The casing 3 is 110

provided with apertures 32, one for each of the sleeves 2, and positioned to register with a single one of a series 25 of figures arranged upon the sleeve. Other suitable 5 indicating means might be employed in connection with these figures 25, but the aperture 32 forms a convenient means and one which is now preferred by me. While I have described the sleeve 2 as being rotatable 10 within a fixed casing 3, it is evident that a reversal of this arrangement would still be within the scope of my invention.

The figures 25 are arranged upon the periphery of the sleeve 2 in some progressive curve. By this term I mean some curve which does not repeat itself within the lineal distance required by the number of figures to be employed. The curve may be a spiral, figure 8, or as shown herein, 20 a helix, depending in large measure upon the character of the rotative member 2. These figures represent the distance in inches between the path of the saw and the log engaging face of that knee 11 which 25 corresponds to this particular sleeve 2. As most set-works provide a wide range of setting, for instance, a range of seventy-two inches, and as it is important to keep the size of the register down but yet to make 30 the figures in the series 25 clearly visible to the sawyer throughout the movement of the set-works, the desirability of arranging the figures in a helix or other similar curve will be apparent.

35 In order to maintain the proper figure in registry with the aperture 32, it is necessary to move the sleeve 2 bodily in an amount corresponding with the pitch of the helix upon which the figures 25 are arranged. The means which I employ for this purpose are best shown in Figure 3, although I do not desire to limit myself only to these means. I provide upon the hub 26 of the sleeve, a helical groove or screw 40 thread 27 having a pitch equal to the pitch of the helical series of figures 25. This is engageable by a suitable nut, which as shown takes the form of a finger 33 depending from a rod 34 which is fixed in the 45 casing 3. A set screw 35 may be employed to retain the rod 34 fixed in position, and this permits adjustment of the sleeve relative to the aperture 32.

In Figure 3 I have illustrated the sleeve 50 2 as having its periphery cut away throughout the greater extent thereof, and covered with a transparent or translucent sheet 28 whereon the figures 25 are placed. This permits the employment of a light 36 within 55 the casing 3 and within the sleeve 2 to illuminate the figure which is opposite the aperture 32.

As the individual sections 13 of the con-

trol shaft are rotated to vary the setting of the knee 11 controlled thereby, this movement will be communicated to the sleeve 2 which corresponds to that knee. The sleeve will be rotated and will also be axially moved to maintain the line of figures in registry with the aperture 32. Rotation of 60 the sleeve will bring into registry with the aperture 32 the figure corresponding to the number of inches the face of the knee 11 is spaced from the path of the saw. Changes in position of the knee will cause a corresponding change in the setting of the register so that the figure appearing through the aperture 32 will always indicate the exact setting of the knee to which it corresponds. The various sleeves are independently movable because of the fact that the various knees 11 may be set independently. The sawyer thus can always ascertain the setting of the various knees of the set-works, for the purposes set forth heretofore. 75

What I claim as my invention is:

1. In a set-works, in combination with the carriage, a plurality of knees, a set shaft on the carriage formed as a plurality of independently-operable sections each corresponding to one of said knees, a taper register offset from the set shaft and adapted to be set with its axis at an angle thereto, said register including a plurality of movable indicators each corresponding to its respective section of the set shaft and connected knee, stub shafts operatively connected each to its respective indicator, other stub shafts each operatively connected to its respective set shaft section, and a flexible drive connection between the corresponding stub shafts. 90

2. In a set-works, in combination with the carriage, a plurality of knees, a set shaft on the carriage formed as a plurality of independently-operable sections each corresponding to one of said knees, a taper register offset from the set shaft and adapted to be set with its axis at an angle thereto, said register including a plurality of movable indicators each corresponding to its respective section of the set shaft and connected knee, stub shafts operatively connected each to its respective indicator, other stub shafts each operatively connected to its respective set shaft section and substantially in a common plane with but at an angle to its corresponding indicator stub shaft, and a flexible drive connection between each pair of corresponding stub shafts 110 comprising a pair of universal joints and a telescoping shaft section therebetween. 115

Signed at Seattle, King County, Washington, this 21st day of October, 1921.

GILBERT LOKEN.
